PROCESS AND A DEVICE FOR MANUFACTURING BRIQUETTES BY COMPRESSION

Willem Bolk, Arnhem, Netherlands, assignor to
 Naamloze Venootschap-Maatschappij tot
 Exploitatie van "ten Bosch Octrooien N. V.",
 Arnhem, Netherlands, a corporation of the
 Netherlands

Application May 10, 1935, Serial No. 20,843
 In Germany July 10, 1934

2 Claims. (Cl. 25—45)

The invention relates to a process and to a device for manufacturing briquettes by compression from material in powder form without the use of a binding agent. According to this process the material is to be subjected to a very high pressure, care being taken that the air or other gases accumulated in the material, are removed as much as possible.

Up to the present it has not been possible to withdraw the said gases completely. It was customary to leave open a narrow slit between the compressing ram (if desired the counter-ram) and the wall of the mould in order to enable the gases pressed from the material to escape through the same.

This, however, does not work very well in actual practice, since by the high pressure needed for compressing the material, particles of this material are driven into the slits, clogging up the same. A certain amount of the gases will then remain in the material which gas is compressed along with it. Since the said gases will expand when the briquettes are leaving the press, the briquettes will become porous and inclined to fall apart. If the slit is made a little wider, so that it may not readily become clogged, there always is the possibility of a part of the material being blown through the said slit together with the escaping gases, in which case the compression will not be sufficiently strong on account of the shortage of material.

The present invention has for its purpose to improve the above process so as to render possible the withdrawal of the major part of the gases present in the material.

According to the invention compression is carried out in at least two phases in such a way that at a predetermined moment during the final phase of the compressing process one or more outlet openings are formed through which the gases still present in the mass are enabled to escape.

Devices for carrying out this method may be constructed in various ways. It is possible, e. g., to use moulds comprising one or more parts pressed together from the outside by means of bolts or otherwise in such a way that the mould at a given interior pressure is entirely closed.

The closing force acting from the outside is then chosen in such a way that towards the end of the compressing action it can no longer offer sufficient resistance, so that one or more small apertures are formed through which the gases can escape.

An embodiment of such a compression mould is illustrated in the accompanying drawing in which

Fig. 1 is a top view, and

Fig. 2 is a section through the said mould according to the line II—II in Fig. 1.

It is shown in the drawing that the compression mould consists of four parts 1, 2, 3, 4, each provided with a back 5. The said backs are mutually connected by draw springs 6, the tension of which may be adjustable, if desired.

The tension of the springs has been taken so that if a given pressure is exerted between the rams 7, 8 on the contents of the compression mould, the spring tension is partly overcome and a narrow slit is formed between the adjacent surfaces of the parts 1, 2, 3 and 4.

Instead of the compression mould the ram or the counter-ram may be constructed so that a split enabling the gases to escape will be formed in the same at the end of the compressing action.

It is also possible to make the compression mould itself of such material that towards the end of the compressing action the slit between the ram or the rams and the body of the mould becomes a little wider.

I claim:

1. A molding device of the character described comprising a plurality of members, means for yieldably securing the members together, whereby the members may become slightly spaced from one another when the pressure within the mold exceeds a certain predetermined value.

2. A process for manufacturing briquettes from material in powdered form consisting in applying increasing pressure to the material in a mold, during the final phase of which application of pressure the mold is caused to expand to form slight openings for permitting the compressed gases contained in the material to escape.

WILLEM BOLK.
